D. SUTTON.
Felting Machine.
No 6607X Patented Jun. 13, 1831.

David Button
Button Patent

6607X
6/13/1831

The Schedule referred to in these Letters Patent and making part of the same containing a description in the words of the said David Button himself of his improvement in the art of sizing hat-felts and mapping or coating the exterior of hat bodies with fur by steam.

To all to whom these presents shall come - - - - -
Be it known that I, David Button of Lancaster, Conn.
by ff. of year and and State of Kentucky, have invented
a most ready useful improvement in the art of sizing
hat-felts and mapping or coating the exterior of hat bodies
with fur by steam, and that the following is a full and
exact description of the construction and operation of said
machine and of its application to the purposes claimed
by me.

1st. A boiler in which the steam is gener-
ated, that will contain fifteen gallons, the size of which
however may be enlarged or diminished to suit the quan-
tity of work to be performed - the boiler may be made
of sheet iron or any other suitable material, the form of
which is not material, on which is fixed a safety valve
to prevent too great an accumulation of steam - - -

2nd. An Octagon or hexagon cylinder with two flat
ends 24 inches apart 4 feet in diameter which may
be enlarged or diminished (without paying much regard
to these proportions) so as to accommodate it to the work to
be performed, in which is a small door made tight by
which the hat-felts or bodies are passed into it in the
use of one end of this cylinder is a gudgeon upon which is
fixed a crank 18 inches long by means of which when the
cylinder is placed on a suitable frame for the purpose it may
be turned by the hand - in the centre of the other end of the
cylinder

6/13/1831 6607X

cylinder is a hollow gadgeon 3rd A frame of any convenient construction in which inter for the gadgeons of the cylinder are placed. 4th A small tube or pipe made of copper or other suitable material by which the steam is conveyed from the generator through the hollow gadgeon into the cylinder. 5th After fitting the mapping or coating on the hat bodies they are then placed in the cylinder in a wet state, the cylinder having no water in it, the steam is then let into the cylinder as above described, after it becomes hot it is then revolved by means of the crank a short time, say from twenty to thirty minutes (according to the fur you map with); thus by the power of the steam and the revolution of the cylinder the body is prepared to kindly receive the map and it is forced into the body in a neat and durable manner - as many hats may be placed into the cylinder as can be revolved. 6th To reduce or size hat felt either wool or fur after they are shrunk a little say one eighth they are placed in the cylinder in a wet state (the cylinder having no water in it) the steam is then let in upon them until they are made hot and then by revolving the cylinder a short time say about twenty or thirty minutes they are reduced to the proper size for mapping or coating. Now that to which I claim the right of exclusively reserving or reserving to others to be used, is the Application of steam as above described to the reducing or sizing of hat felts either wool or fur and the mapping of hat bodies either wool or fur.
